United States Patent Office

Des. 193,307
Patented July 31, 1962

193,307

CLOCK

Steven T. Bille, West New York, and Knute Heinz, Pearl River, N.Y., assignors to The Curtis Publishing Company, Philadelphia, Pa., a corporation of Pennsylvania

Filed Dec. 5, 1961, Ser. No. 67,833

Term of patent 14 years

(Cl. D42—7)

Fig. 1

Fig. 2

Fig. 3

Fig. 4

Fig. 5

FIG. 1 is a front view in perspective of a clock including a clock face showing our new design, the clock face including the numerals being embroidered on cloth;

FIG. 2 is a top plan view thereof;

FIG. 3 is a left-side elevational view thereof;

FIG. 4 is a rear elevational view thereof; and

FIG. 5 is a right-side elevational view thereof.

We claim:

The ornamental design for a clock, as shown and described.
